KNITTING MACHINE

Robert Kirkland Mills, Sherwood, Nottingham, England, assignor to Wrightwear Limited, Sutton-in-Ashfield, Nottinghamshire, England

Application November 26, 1937, Serial No. 176,747
In Great Britain November 27, 1936

3 Claims. (Cl. 66—158)

This invention comprises improvements in or relating to knitting machines and is particularly, although not exclusively, applicable to circular knitting machines of the multi-feeder type. In 5 multi-feeder circular machines there is commonly employed automatic stop mechanism adapted to be brought into operation by the displacement of pivoted dropper elements co-operating with individual threads supplied to the needles; these 10 droppers are normally supported in a raised position by the threads and the breakage of a thread or the exhaustion of a thread supply causes the dropper appertaining to said thread to fall and to bring into operation a device or mechanism 15 for stopping the machine. In such automatic stop mechanism the falling movement of a dropper, in addition to bringing the machine to rest, also brings into operation a device which causes all of the several droppers in the machine to 20 spring or rise to a substantially vertical inoperative position, that is to say to a position beyond the normal inclined operative position, the droppers being again brought into operation when the machine is restarted.

25 Now it has been found that when working with silk, art silk and similar yarns of a smooth or glossy nature on a machine employing droppers as above-described, the disadvantage exists that when the machine is stopped at any time by hand 30 in the normal working operation, the droppers suspended on the threads gradually fall until one or more of same reaches the position at which the catch mechanism is operated to raise all of the droppers to the vertical inoperative position, and 35 when this occurs the thread which has been drawn from the supply by the falling droppers hangs loosely about the raised droppers and becomes ravelled. The reason why the droppers gradually move down of their own accord when 40 the machine is stopped is that the glossy or slippery surface of the silk or art silk yarn, or yarn having similar characteristics, offers a minimum of frictional resistance to draw-off, and the weight of the droppers is sufficient to overcome 45 this resistance. When working with yarn of a less smooth or slippery nature, e. g., wool or cotton, the possibility of the droppers falling of their own accord when the machine is at rest is minimised or eliminated. If, in an endeavour 50 to overcome the above disadvantage, lighter droppers are employed, such droppers although effective when working with comparatively smooth or slippery yarn such as art silk, would be ineffective when working with the rougher yarn such as cotton or wool.

An important object of the present invention, therefore, resides in the provision of means whereby droppers of uniform weight can be employed with equal efficiency for use with all classes of yarn of any count. The invention is, however, 5 particularly applicable to stop mechanism of the type comprising at least one movable thread-engaging feeler or dropper which moves upon breakage of the thread or failure of the thread supply to bring into operation the device or mechanism 10 for stopping the machine. This stop mechanism is hereinafter referred to as "stop mechanism of the type specified"; and according to the present invention there is provided, in or for a knitting machine, stop mechanism of the type specified, 15 characterized by means operating automatically upon stoppage of the machine to prevent movement of said feeler or dropper, and/or to prevent further withdrawal of thread, until the machine has again started. As will readily be appreciated 20 from the foregoing discussion of the disadvantages at present inherent in stop mechanism, the said means preferably operates automatically upon manual stoppage of the machine, and the mechanism embodies a plurality of droppers and 25 means whereby the descent of any dropper, in addition to stopping the machine, causes the dropper to rise to a high position.

This invention also provides, in or for a multi-feeder circular machine, the combination with 30 stop mechanism comprising a movable thread-engaging feeler for each feed, each of which feelers is normally positioned by the thread that it engages and is movable, upon breakage of the thread or upon failure of the thread supply, to stop 35 the machine automatically, of control means for stopping and starting the machine manually, and means, interconnected with said control means, for restraining the feelers from movement when the machine is stopped manually and for releasing them when the machine is again started. Preferably, means are provided for ensuring that a slight delay or lag occurs between the starting 40 of the machine and the release of the feeler or dropper or of each of them in the case of a multi-feeder machine. For this purpose there is preferably a control member which is movable from a stopping position to a starting position and is also capable of additional movement after that necessary to start the machine, and means where- 45 by said additional movement serves to free the feeler or dropper.

In order that the invention may be better understood reference will now be made to the accompanying drawings, in which

Figure 1 is a sectional elevation of the super-structure of a multi-feeder circular knitting machine equipped with stop mechanism according to this invention;

5 Figure 2 is a plan thereof; while

Figure 3 is a view of a portion of the mechanism looking in the direction of the arrow 3 in Fig. 1.

Each thread T, from the supply cones or the 10 like mounted in the customary manner above the machine, is guided in its passage to the needles (not shown) through eyes 10 or their equivalent. In its passage between certain of the eyes the thread runs through the ring 11 15 of a dropper which has a rod 12 extending radially inwards towards the centre of the machine and suitably pivoted in the bracket 13. As will readily be understood the tension of the thread running through the dropper ring when the machine is knitting keeps the dropper in a raised 20 position. When that tension is relaxed, however, the dropper falls, pivoting about the axis of the rod 12.

At each feed in a multi-feeder machine there 25 is mechanism identical with that described. The various rods 12 at their inner ends pass into a stop box 14 containing stop mechanism of any known or approved kind. This stop mechanism is so constructed that the part-rotary movement of any rod 12 consequent upon the fall of a dropper releases with a sharp movement a trip member here illustrated as a vertical pivoted rod 15, and also causes all the droppers to rise 30 to a high, inoperative, position. When the rod 15 makes an abrupt turning movement an outward movement is communicated to the radial rod 16 which rotates a small catch 17. The latter is therefore released from engagement with the end 18 of a trip lever which is associated 35 with a lever 19 pivoted at 20 and is spring-biased in a clockwise direction about its pivot. The outer end of said lever 19 co-operates with a ramp or incline 21 on a lever 22 pivoted at 23, with the result that the end of the lever 22 40 formed with the ramp 21 is depressed and the other end raised. This causes said other end to disengage from a suitable recess in a catch bar 24 and permits a lever 25 to move under the influence of a spring indicated at 26 to stop the machine. Said lever 25 may control a belt 45 shifter, a clutch or any other suitable machine-stopping device. By way of example it is illustrated as controlling a dog clutch 27.

In addition to its automatic operation as just 50 described the said lever 25 may be moved manually to bring the machine to a standstill, and according to this invention means are incorporated whereby such manual movement of the lever 25 also prevents each dropper from falling. 55 The cause of the tendency to fall exhibited by the droppers after the machine has been stopped manually and the consequence thereof is hereinafter explained.

On the lever 25 there is a ramp 28 co-operating 60 with an adjustment screw 29 at the end of a lever 30. This lever is connected by rods 31, 32, and bell-crank-lever 33 to a radially movable cam member 34, a spring 35 being provided and so arranged that said cam member is biased 65 inwards.

Above the box 14 there is a ring 36 suitably supported on a stationary part of the machine and provided with a guide 37 for the cam member 34. Upon this ring 36 a pin ring 38 is movably 70 mounted and is drawn by a tension spring 39

in a clockwise direction. This pin ring carries a small depending pin 40 which extends down through a slot 41 in the ring 36 and is equipped with a roller 42 co-operating with the inclined face of the cam member 34. Hence when the 5 lever 25 is moved to stop the machine and the cam member 34 is drawn inwards by spring 35 the pin ring 38 is moved in a clockwise direction. This pin ring is equipped with radial projecting pins 43, one for each dropper, and by this movement each pin is displaced (from the position shown in chain-dotted lines in Fig. 3 to that shown in full lines) to prevent the associated dropper from falling.

When the lever 25 is moved to start the machine the cam member 34 is drawn outwards and the pins such as 43 are therefore moved away from the droppers which are then free to operate in response to breakage of the thread or failure of the supply thereof.

Means are provided, however, for ensuring that movement of the pin ring 38 to release the droppers does not take place until shortly after the machine has commenced to knit. As a result the machine makes a few revolutions and knits up the slack in the threads before the droppers are freed, and when the latter are freed they are supported by the tensioned thread that is travelling to the needles. To achieve this object in the construction illustrated the clutch 21 and the ramp 28 are so arranged that, as is readily discernible from Fig. 1, the ramp 28 does not rock the lever 30 until after the clutch has engaged.

I claim:

1. In a circular knitting machine having manually operable control means for starting and stopping the same, and automatic stop mechanism of the type specified, including a movable thread feeler arranged upon thread breakage or failure of the thread supply to actuate said mechanism to automatically stop the machine, the combination of an arcuately movable ring provided with a projection arranged to be moved into and out of engagement with said feeler; means operable by said control means arranged to induce movement of said ring, when the machine is stopped by hand, to cause its projection to engage the feeler and thereby prevent the latter from actuating said automatic stop mechanism, said means also functioning to induce movement of the ring to disengage the projection from the feeler when the machine is manually re-started through said control means; and means for delaying said disengagement of the projection from the feeler until the machine is in motion.

2. A machine according to claim 1, wherein the manual control embodies a member which is movable from a machine-starting to a machine-stopping position, and also has an additional movement beyond that necessary to start the machine; and means whereby the freeing of the thread feeler from engagement with the projection on the movable ring is effected by said additional movement so that a slight delay or lag is obtained between the starting of the machine and the release of the feeler.

3. A circular knitting machine according to claim 1, embodying a plurality of thread feeds and having a thread feeler associated with each feed; and a projection on the movable ring for engaging with each feeler.
